UNITED STATES PATENT OFFICE.

HAROLD DE FOREST ARNOLD, OF EAST ORANGE, NEW JERSEY, ASSIGNOR TO WESTERN ELECTRIC COMPANY, OF NEW YORK, N. Y., A CORPORATION OF ILLINOIS.

ELECTRIC RELAY APPARATUS.

1,118,175.

Specification of Letters Patent.

Patented Nov. 24, 1914.

Application filed January 8, 1914. Serial No. 811,034.

To all whom it may concern:

Be it known that I, HAROLD DE FOREST ARNOLD, a citizen of the United States, residing at East Orange, in the county of Essex and State of New Jersey, have invented a certain new and useful Improvement in Electric Relay Apparatus, of which the following is a full, clear, concise, and exact description.

10 This invention relates to electric relay apparatus of the gaseous type; its objects are to prolong the life of such apparatus and to increase its efficiency.

In the use of the mercury arc type of relay disclosed in a prior application of this inventor, Serial No. 709,445 filed July 15, 1912, an effect has been observed which is known as "blackening" of the inside surface of the tubular vessel. This blackening occurs where the gas is in an active state of ionization and is most prominent in the region of the auxiliary electrodes. The deposit which causes it is electrically conductive so that in time a short circuit occurs 25 between the electrodes leading-in conductors. It has been found that blackening is lessened and the life of the apparatus is thereby increased in accordance with this invention by attaching the leading-in conductors to the auxiliary electrodes at some point removed from the edges thereof, preferably at some central point. Increased efficiency is secured by flattening the tubular vessel at the portion thereof adjacent

30 35 40 45 the electromagnet, whereby the pole pieces of the magnet may be brought close together and the magnetic field strengthened. A further improvement in efficiency is secured by the use of auxiliary electrodes of magnetic material. The material is preferably iron as it is the best magnetically and does not combine easily to form an amalgam with mercury. The auxiliary electrodes may be formed of a plurality of magnetic plates held together at a spaced distance apart by non-magnetic binding material such as aluminum. These plates preferably lie transverse to lines of force produced by the electromagnet. Two such auxiliary elec-

50 55 trodes may be connected in a divided output circuit and symmetrically placed side by side in the flattened portion of the tube so that the external contour of the two together conforms generally to the contour of the inner surface of the tube, in which case the

ionized stream flows along the inner walls of the iron plates and not at all or at least only to a small extent between the electrodes and the walls of the vessel.

The invention will be more fully understood by reference to the accompanying drawings wherein—

Figure 1 shows a system of circuits and apparatus representing one embodiment of this invention; and Fig. 2 shows in cross section the apparatus of Fig. 1, separated from the circuits, on line 2—2 thereof.

Referring to the drawings, the means for producing the ionized stream, which in this instance has been shown as a mercury arc apparatus, comprises a main chamber 1 having a tapered lower portion 2, which joins a condensing chamber 3, together with a mercury cathode 4, an anode 5 of iron or other suitable material, and a starting anode 6 of iron or other suitable material. In order to prevent the breaking of the tube due to the falling of the mercury should the position of the tube be reversed, the upper portion of the condensing chamber 3 is provided with a cushion in the form of a restricted neck 8 and a ball-like portion 9 adjacent the sealed end. The main chamber 1 for a portion of its length is flattened, as at 7. Supported within the main chamber 1 and confined within the flattened portion 7 are a pair of auxiliary cathodes 11, 12, each of which is formed of a plurality of magnetic plates 13, 13, preferably of iron, held together at a spaced distance apart by means of a binder 14, and rivets 10 of aluminum or other suitable non-magnetic material. The use of non-magnetic material as a binder in spacing the magnetic plates 13, 13 of each auxiliary cathode prevents the shunting of the lines of force through that portion of the cathodes including the binder 14, which would occur were the binder made of magnetic material.

As shown in the drawings, the two cathodes 11, 12, are slightly separated from each other and from the walls of the chamber. The outer plates of each cathode are preferably longer than the others thereof, so that the separation between the edges of the opposite outer plates of the two cathodes will be slight and will therefore, in effect, form an almost closed tube through which is confined the path of the ionized stream, thereby reducing to a minimum the blacken-

ing of the walls of the main chamber 1 adjacent the opposing edges of the outer plates 13, 13 of the auxiliary cathodes 11 and 12. Leading-in conductors, preferably of platinum wire, are provided for the several electrodes of the device. In order that the blackening of the leading-in conductors 15, 16 for the auxiliary cathodes 11 and 12, may be reduced to a minimum and the life of the device correspondingly increased, the leading-in conductors 15 and 16 are attached to the auxiliary cathodes 11 and 12 respectively, at points removed from the edges thereof, preferably at some central point.

As a means for deflecting the ionized stream, there has been shown an electromagnet 20, the means of support of which is not shown. Such magnet comprises a pair of coils 21 and 22 surrounding inwardly extending pole pieces, the outer ends of which are joined by a semi-circular yoke 23. The pole pieces present their faces to opposite sides of the main chamber 1 in the region of the auxiliary cathodes 11, 12 so that the lines of force between the pole pieces lie in a direction transverse to the direction of flow of the ionized stream in the chamber 1, and operates to deflect the stream in the direction of one auxiliary cathode or the other, according to the direction of the current in the magnet coils. Due to the main chamber 1 being flattened at 7, adjacent the auxiliary cathodes 11 and 12, the faces of the pole pieces may be brought close together and the magnet field strengthened.

The system shown in Fig. 1 comprises substations A and B, which are connected together by means of line wires 31 and 32 in which there is connected a relay station C. At each substation there is provided a receiver 33 in series with the line wires 31 and 32, and an induction coil secondary 34, the primary 35 of which is in series with a transmitter 36 and a source of current 37. At the substation C there is provided a transformer 40 having four secondary windings, 41 and 42 of which are connected in line 31, and 43 and 44 of which are connected in line wire 32. This transformer 40 has two primary windings 45 and 46, which are in inductive relation with the secondary windings thereof. The point joining the transformer primaries 45 and 46 is connected to the negative pole of a battery 53, the positive pole of which is connected to the anode 5. The other leads from the transformer primaries 45 and 46 are connected to the cathodes 11 and 12 respectively. Primary winding 50 of a transformer 51 is connected to the middle points joining the transformer secondaries 41 and 42, and 43 and 44 respectively, and the secondary 52 thereof is connected in series with the windings 21 and 22 of the electromagnet 20. The negative pole 65 of battery 53 is also connected to the mer-

cury cathode 4 through a resistance coil 54 and an impedance coil 55. The positive pole of the battery 53 is also connected to the anode 6 through the starting key 56.

The impedance coil 55 and resistance coil 54 provide a path for the mercury arc circuit to maintain a steady flow of current therein, which, when once established, as by tipping the tube, closing the circuit at the starting key 56 over the path 53, 55, 54, 4, 6, 56, 53, and then releasing the key 56, is maintained automatically over the path 53, 55, 54, 4, 2, 1, 5, 53, which includes the ionized arc stream in the main chamber 1, said stream being confined at the flattened portion 7 of the main chamber 1 within the area bounded by the outer plates 13, 13 of the auxiliary cathodes 11 and 12. This stream in passing through this path fills the region confined within these plates of the auxiliary cathodes 11 and 12 and renders the auxiliary circuit conductive so that current flows from battery 53, dividing through the primary windings 45 and 46 of the transformer 40, to the auxiliary cathodes 11 and 12, to and through the ionized vapor therebetween and by way of the anode 5 back to the battery 53. The primary coils 45 and 46 of the transformer 40 are wound differentially in the auxiliary circuit, that is to say, in such a direction with respect to each other that the core thereof under normal conditions of the circuit is not magnetized. The normal current flows equally, or approximately so, in the two branches, this being due to the symmetrical arrangement of the auxiliary cathodes 11 and 12 with respect to the ionized vapor in the space between them. When, however, the electromagnet 20 is energized by current received over the circuit from either station A or B, a magnetic field is produced which deflects the stream through one electrode or the other. The effect of this is a change in the distribution of ionization in the field or space between the auxiliary cathodes, and current will flow with increased strength through one primary winding of the transformer and with decreased strength through the other, thereby inducing current in the secondary windings, which is transmitted over the line wires to the other station and recorded or made manifest in the receiving instrument 33.

What is claimed is:

1. An electric relay apparatus comprising means for producing an ionized stream, an output circuit including an auxiliary cathode of magnetic material immersed in said stream, and an input circuit including electromagnetic means external to said circuit for variably deflecting said stream toward and from said auxiliary cathode.

2. An electric relay apparatus comprising a tubular vessel, means for producing an

ionized stream therein, an output circuit including an auxiliary cathode of magnetic material immersed in said stream, and an input circuit including an electromagnet external to said stream for variably deflecting said stream toward and from said auxiliary cathode.

3. In an electric relay apparatus, the combination of a tubular vessel flattened at one portion, means for producing an ionized stream therein, an output circuit including an auxiliary electrode in said vessel at the flattened portion thereof, and an input circuit including an electromagnet external to said vessel for variably deflecting said stream, said magnet having its pole pieces adjacent the flattened sides of said vessel.

4. An electric relay apparatus comprising means for producing an ionized stream, an output circuit including an auxiliary cathode immersed in said stream, and an input circuit including an electromagnet external to said stream for variably deflecting said stream toward and from said auxiliary cathode, said cathode comprising a plurality of plates of magnetic material positioned transversely to the lines of force from said electromagnet.

5. In an electric relay apparatus, the combination of a tubular vessel flattened at one portion, means for producing an ionized stream therein, an input circuit including an electromagnet external to said vessel for variably deflecting said stream, said electromagnet having its pole pieces adjacent the flattened sides of the vessel, and an auxiliary electrode in said vessel at said flattened portion thereof, said electrode comprising a plurality of plates of magnetic material lying transversely to the lines of force between the poles of said electromagnet.

6. An electric relay apparatus comprising means for producing an ionized stream, an output circuit including an auxiliary cathode immersed in said stream, and an input circuit including an electromagnet external to said stream for variably deflecting said stream toward and from said auxiliary cathode, said cathode being partly of magnetic and partly of non-magnetic material.

7. In an electric relay apparatus, the combination with means for producing an ionized stream, and an input circuit including an electromagnet external to said stream for variably deflecting it, of an output circuit

including an auxiliary electrode immersed in said stream, said electrode being composed partly of a plurality of plates of magnetic material lying transversely to the lines of force from said electromagnet, and partly of non-magnetic material for spacing the said plates apart and holding them together.

8. In an electric relay apparatus, the combination of a tubular vessel flattened at one portion, means for producing an ionized stream therein and an input circuit including an electromagnet external to said vessel for variably deflecting said stream, said electromagnet having its pole pieces adjacent the flattened sides of the said vessel, and an auxiliary electrode in said vessel at the flattened portion thereof, said electrode comprising a plurality of plates of magnetic material lying parallel to said flattened sides of the vessel and non-magnetic binding material for holding the said plates together at spaced distances apart.

9. In an electric relay apparatus, the combination with a tubular vessel, means for producing an ionized stream therein and an input circuit including electromagnetic means external to said stream for variably deflecting it, of a divided output circuit including a pair of auxiliary electrodes each partly of magnetic and partly non-magnetic material and immersed side by side in said stream, said electrodes forming together an inclosure for a portion of the magnetic stream and conforming generally to the contour of the tubular vessel.

10. In an electric relay apparatus, the combination with a tubular vessel, means for producing an ionized stream therein, and an input circuit including an electromagnet external to said vessel for variably deflecting said stream, of an output circuit including an auxiliary electrode immersed in said stream, said electrode conforming generally to the contour of the inner surface of said vessel and being closely adjacent thereto, and a leading-in wire for said electrode attached thereto away from the edges thereof.

In witness whereof, I hereunto subscribe my name this 5th day of January A. D., 1914.
